W. E. HOWDEN

ADJUSTABLE DRAFTING INSTRUMENT

Filed April 12, 1924

Inventor:
Walter E. Howden.
by J. G. Fletcher,
His Attorney.

UNITED STATES PATENT OFFICE.

WALTER E. HOWDEN, OF EDWARDSVILLE, ILLINOIS.

ADJUSTABLE DRAFTING INSTRUMENT.

Application filed April 12, 1924. Serial No. 705,987.

This invention relates to an improvement in drafting instruments and pertains more particularly to that class of instruments known as irregular curve or arc forming devices.

Another object of the invention is in providing an improved instrument for making or forming circles or curves which will in some instances supplant the beam form of compass now in use.

A further object of the invention is in providing an improved adjustable curve forming instrument which is without a centering point.

Other and further objects will appear in the specification and be specifically pointed out in the appended claims, reference being had to the accompanying drawings, exemplifying the invention, and in which:

Figure 1 is a plan view of this improved adjustable drafting instrument.

Figure 2 is a fragmentary section taken approximately on the line 2-2 of Fig. 3.

Figure 3 is a vertical transverse section taken on the line 3-3 of Fig. 1.

Figure 4 is a plan view of the instrument on a reduced scale showing it adjustable to form a concave line.

Referring by numerals to the accompanying drawings, this improved instrument comprises a length of a round and resilient steel rod bent into an oblong shape and forming a pair of parallel legs 1 and 2 and end portions 3, the leg 2 being formed from the ends 4 of the resilient steel rod, and having said ends bent so as to be in alinement with one another as shown in Fig. 2.

The ends 4 are each threaded as shown in Fig. 2, one end having a right hand thread 5 and the other end being provided with a left hand thread 6, said threaded ends 5 and 6 being normally held a distance apart, and for engagement with said threads is an adjusting sleeve 7 having interior right hand threads 8 at one end and at the opposite end interior left hand threads 9, the threads 8 engaging the right hand threads 5 of the end 4, and the threads 9 engaging the left hand threads 6 of the other end 4 of the leg 2.

Loosely mounted over the ends 4 of the leg 2 are a pair of bearings 10 of a holding plate 11, each of said bearings having a tapered bore 12 and in which the small end of each bore is arranged outwardly.

This improved drafting instrument is

adapted to take the place of the well known beam-compass and in addition thereto is adapted to be used in making irregular curves.

In the use of a beam-compass, it is often inconvenient to establish the centering point thereof in instances where a curved line is to be made on a large radius, as it is often necessary to describe a line upon a drawing sheet in such a position thereon where it is necessary to locate the centering point of the beam-compass at a point removed from the drawing board on which the drawing sheet is located. With this improved adjustable drafting instrument, no centering point is necessary as it can be located upon the drawing sheet in a manner as is the ordinary irregular curve or scroll.

In the operation of this improved instrument, the outer edge 13 of the leg 1 serves as the marking or ruling edge and when it is desired to shape or adjust the leg 1 to a desired form or size of curve, the adjusting sleeve 7 is turned in a right hand direction in which the lengths 4 of the leg 2 will be drawn towards each other into the sleeve 7, thereby shortening the length of the leg 2 and drawing the inner end 14 of each of the end portions 3 inwardly thereby causing the leg 1 to be flexed outwardly as shown in both full and dotted lines in Fig. 1.

When the desired formation of the leg 1 has been attained, the left hand of the operator is firmly held upon the holding plate 11 so that the draftsman can apply a marking tool to the ruling edge 13 of the leg 1 and locate the desired curved formation upon the drawing sheet.

If it is desired to produce a concave curve, the adjusting sleeve 7 is turned in the direction opposite to that which it was turned for causing the leg 1 to be forced outwardly as shown in Fig. 1, said opposite turning of the sleeve 7 forcing the threaded ends 5 and 6 of the leg 2 away from each other within the sleeve 7 in which the inner end 14 of each of the end portions 3 will be forced outwardly thereby causing the leg 1 to be flexed inwardly as shown in Fig. 4.

The tapered bore 12 provided in each of the bearings 10 of the holding plate 11 is for the purpose of preventing binding of said bearings upon the ends 4 of the leg 2 during flexing of the leg 2.

Transversely disposed apertures 15 are

provided in the adjusting sleeve 7 for the introduction of a manipulating tool 16 for making said sleeve turn with ease.

On account of the holding plate 11 being loosely mounted on the leg 2, said plate will readily adapt itself to flatly engage the drawing sheet.

It is obvious that the length of the round steel from which the legs 1 and 2 are comprised will be resilient.

To aid the flexing qualities of the legs 1 and 2, notches 17, shown by dotted lines in Fig. 1, can be provided on one side of each of said legs.

15 What I claim is:—

1. A drafting instrument made from a length of resilient material bent into an oblong shape having the ends of the material length disposed on one side of the oblong, and 20 drawing means connected to the ends of the material length for flexing a portion of the material length.

2. A drafting instrument comprising a length of resilient steel rod bent into an ob- 25 long shape and forming a pair of paralleling

legs, one of said legs being provided with adjacent aligning end portions bearing right and left hand threads respectively, and a turnable member mounted on said end portions bearing interior threads for respective engagement with said right and left hand threads of said end portions.

3. A drafting instrument comprised of a pair of paralleling legs, one of said legs being provided with adjacent alining end portions bearing right and left hand threads respectively, a turnable member mounted on said end portions bearing interior threads for respective engagement with said right and left hand threads of said end portions, and a 35 holding plate swingably secured to the leg having the threaded ends.

4. A drafting instrument comprising a length of resilient steel rod bent into an oblong shape and forming a pair of parallel legs, one 45 of said legs being provided with alining spaced apart end portions, and drawing means co-operable with each of said end portions adapted to flex both of said legs.

W. E. HOWDEN.
